CLAIM

The ornamental design for a child's chair, as shown and described.

DESCRIPTION

FIG. 1 is a front perspective view of a child's chair showing our new design wherein the arms are in an open position;

FIG. 2 is a front perspective view thereof wherein the arms are in the closed position;

FIG. 3 is a side elevational view thereof, the opposite side elevational view being identical thereto;

FIG. 4 is a front elevational view thereof;

FIG. 5 is a rear elevational view thereof;

FIG. 6 is a top plan view thereof; and

FIG. 7 is a bottom plan view thereof.

FIG. 1

FIG. 2

FIG. 3

FIG. 4
